UNITED STATES PATENT OFFICE.

HARRY W. DENHARD, OF SAN FRANCISCO, CALIFORNIA, ASSIGNOR, BY MESNE ASSIGNMENTS, TO THE CUTLER-HAMMER MFG. CO., OF MILWAUKEE, WISCONSIN, A CORPORATION OF WISCONSIN.

ELECTRIC HEATER.

1,103,274.

Specification of Letters Patent. Patented July 14, 1914.

Application filed July 15, 1908, Serial No. 443,682. Renewed November 9, 1912. Serial No. 730,536.

To all whom it may concern:

Be it known that I, HARRY W. DENHARD, a citizen of the United States, residing at San Francisco, in the county of San Francisco, State of California, have invented certain new and useful Improvements in Electric Heaters, of which the following is a specification.

My invention is an improvement upon an application filed by me on the 24 day of June 1908 Serial Number 440,371, in which water is heated in a chamber containing a series of positive and negative electrodes held separated from each other with the space between filled by the liquid to be heated and forming a sufficient resistance for the passage of the current to heat the liquid, the liquid passing in and out of the chamber from a source of supply to the point of use.

In the present form of my invention I have modified the construction of the electrodes as well as the chamber containing the electrodes so as to allow of the inlet and discharge of the water at the same end of the chamber.

In the accompanying drawing, Figure 1 shows my improved heater in elevation with part of the casing broken away to show the interior. Fig. 2 is an end view of the same, parts also being broken away. Fig. 3 is a modification showing part of the casing broken away, and Fig. 4 is an end view of Fig. 3.

The outer receptacle constituting the water heating chamber is of rectangular form in Figs. 1 and 2, the walls being shown at 1, and composed of any suitable metal having an interior facing of non-corrosive material, or the whole receptacle may be made of non-corrosive material. The receptacle is provided with a top or head 3, suitably secured to the walls, while the opposite head is also secured to the walls of the chamber and is provided with a central inlet passage 11 and outlet passage 10. The head 2 carries parallel electrodes 6 insulated from the head by a gasket 21 which also forms a water-tight connection between the electrodes 6 and the cap 2.

The electrodes 6 extend up to near the opposite end of the chamber as shown in Fig. 1, and extend from wall to wall in their width as shown in Fig. 2. Secured to the opposite end of the chamber, that is to the cap 3, through a metallic plate 12, is a sec-

ond set of electrodes, the plate 12 being secured to the cap by a screw 9, the screw passing through an insulating bushing 8 and having a nut upon its opposite end as at 20, the screw forming also the electrical connection with an outside source of current. A gasket 5 is interposed between the plate 12 and the head 3 of the chamber. The electrodes 7 extend from wall to wall as shown in Fig. 2 and to nearly the opposite end of the chamber, these electrodes being parallel to each other and extending outside of the electrodes 6 forming a space between them. The water enters through the passage 11, passing up between the electrodes 6 centrally of the chamber, and then around the opposite ends of the electrodes and through the passage between the positive and negative electrodes flowing out heated at the passage 10. The space between the electrodes being filled with water sets up a resistance to the passage of the current and thus causes the heating of the water.

In Figs. 3 and 4 substantially the same arrangement is shown, except that instead of having the electrodes made of parallel plates they are made of nested cylinders, the center cylinder being of one diameter and the outer cylinder being of a greater diameter, the water passing between the two cylinders and being heated in its passage.

It will be observed that the electric current will continue to flow as long as there is fluid in the channel between the electrodes, but as soon as the water is shut off or ceases to flow and the space between the electrodes has been drained the current will automatically cease.

What I claim is:—

1. An electric fluid heater comprising a casing having an opening at the lower end thereof, a tubular electrode open at one end, and communicating at its other end with said opening, a terminal member carried by said casing and connected with said electrode, a second tubular electrode surrounding said first electrode and spaced therefrom to provide for the flow of fluid therebetween to close the circuit across said electrodes, said second electrode being closed at the end adjacent the open end of said first electrode and a second terminal member carried by said casing and supporting said second electrode by its closed end.

2. An electric fluid heater comprising a

- casing, a pair of tubular electrodes therein, each open at one end and secured to opposite walls of said casing at the other end, one of said electrodes being larger than the other 5 and partially inclosing the latter, a fluid inlet communicating with the supported end of the inner electrode and an outlet connecting with the open end of the outer electrode, whereby all the fluid to be heated is 10 compelled to flow between said electrodes, both said inlet and said outlet being at the lower end of said casing to permit the latter to be drained of fluid, and thus open the circuit between said electrodes.
- 15 3. In an electric heater, a casing provided with an inlet and outlet at the same end thereof, an electrode forming an open-ended chamber communicating with said inlet, and a second electrode forming an open-ended chamber inclosing the open end of 20 said first mentioned electrode and having its open end adjacent the outlet in the casing.
4. In an electric heater, a casing provided with an inlet and outlet at one end 25 thereof, an electrode fixed to one end of said casing and forming an open-ended chamber communicating with said inlet, and a second electrode fixed to the opposite end of said casing forming an open-ended chamber 30 inclosing the open end of said first mentioned electrode and having its open end adjacent the outlet in the casing.
5. An electric fluid heater comprising a casing having an inlet and an outlet at one 35 end of the same, an electrode demountably attached to one end of said casing and directing the fluid toward the opposite end of said casing, and a second electrode demountably attached to the opposite end of 40 said casing and inclosing said first mentioned electrode, said second mentioned electrode directing the fluid directly to the outlet.
6. In an electric heater, the combination of a casing having an inlet and outlet in one of its ends, a conducting plate carried by each end and insulated therefrom, electrodes fixed to each of said plates to form open 45 ended chambers, the open end of one chamber being adjacent the closed end of the other, and terminal connections for said electrodes clamping the same in position in the heater. 50
7. In an electric heater, a casing having an inlet and outlet at one end of the same, conducting plates fixed to the opposite ends of said casing and insulated therefrom, terminal connections for said conducting plates, 55 an open ended electrode fixed to one of said plates and forming a continuation of the inlet, a second open ended electrode fixed to the opposite plate and inclosing the open end of said first mentioned electrode, the open 60 end of said inclosing electrode being adjacent the outlet of the casing.
8. In an electric heater, the combination of a casing having an inlet and outlet, conducting plates fixed to said casing and insulated from the same, electric connections to said plates, an electrode fixed to one of said plates forming an open ended chamber, the closed end of which communicates with said inlet, and a second electrode fixed 65 to the other of said plates forming an open ended chamber surrounding the first electrode and having its closed end adjacent the open end of the first mentioned chamber, and its open end adjacent the outlet of the cas- 70 ing. 75

In testimony whereof I have affixed my signature in the presence of two witnesses this 12th day of June 1908.

HARRY W. DENHARD.
